[57] CLAIM

The ornamental design for a front bezel for a digital cable terminal, as shown and described.

DESCRIPTION

FIG. 1 is a front isometric view of a front bezel for a digital cable terminal, from the front and above;

FIG. 2 is a top plan view of the front bezel for a digital cable terminal;

FIG. 3 is a front elevational view of the front bezel for a digital cable terminal;

FIG. 4 is a bottom plan view of a front bezel for a digital cable terminal;

FIG. 5 is a left side elevational view of the front bezel for a digital cable terminal;

FIG. 6 is a right side elevational view of the front bezel for a digital cable terminal; and,

FIG. 7 is another front elevational view of the front bezel for a digital cable terminal with the numeric and annunciator LEDs visible.

The broken lines which show a partial representation of an enclosure are for illustrative purposes only and form no part of the design claimed.
